UNITED STATES PATENT OFFICE

TREVOR HUGH TURNER, OF LIVERPOOL, ENGLAND, ASSIGNOR TO ASSOCIATED TELEPHONE & TELEGRAPH COMPANY, OF CHICAGO, ILLINOIS, A CORPORATION OF DELAWARE

TELEPHONE SYSTEM

Application filed March 7, 1930, Serial No. 433,872, and in Great Britain March 8, 1929.

The present invention relates to telephone or like systems and is more particularly concerned with systems employing automatic switches which are set by impulses. It is recognized that in such systems the setting impulses suffer both distortion and loss of strength when transmitted over long lines and there is therefore a practical limit to the length of line over which direct impulsion is possible. It is already in general practice to employ so-called impulse repeaters which will strengthen the impulses and thus overcome the difficulty to some extent but the distortion will remain unless special correcting devices are incorporated in the repeaters. Moreover, in repeaters as hitherto generally employed it is usual for the first impulse to produce certain circuit changes whereby the impulsive characteristics of the line are improved, for instance, by the cutting out of impedance the presence of which is desirable for telephone transmission purposes. As a result of this, however, the first impulse probably differs in character from the remaining impulses of a series and this is undesirable from the point of view of ensuring reliable operation. The object of the present invention is to provide an improved repeater circuit by means of which the above difficulties are overcome in a particularly simple manner.

According to one feature of the invention in an impulse repeater for use in telephone or like systems circuit arrangements are provided for absorbing one or more of the initial impulses of a series so that conditions shall have become steady before impulses are transmitted over the outgoing circuit.

According to a further feature of the invention a relay energized at the commencement of the first impulse of an incoming series prepares a circuit for a second relay which is energized on the termination of said impulse and thereupon connects up contacts

for transmitting the remaining impulses of the series to the outgoing circuit.

According to a still further feature of the invention a register sender is arranged to automatically transmit one or more additional impulses in each series of impulses representing digits in the numerical designation of a called line, depending on whether the connection is to be extended through one or more repeaters of the type disclosed herein.

In order that the invention may be clearly understood and readily carried into effect, a telephone system in accordance with the invention will now be more fully described with reference to the annexed drawings. It will be understood, however, that the arrangement described and shown is given by way of example only and that various modifications to the circuit details could be made by those skilled in the art without exceeding the scope of the invention.

Referring now to the drawings, Fig. 1 shows the calling subscriber's loop and the first code selector, Fig. 2 shows a repeater according to the invention, Fig. 3 shows a second repeater stage in the office code translation, Fig. 4 shows the selector and connector switches at the distant exchange and the called subscriber's loop, Fig. 5 shows an A digit switch having access to the register controller and Figs. 6 and 7 show a register controller of standard type which has been modified to suit the requirements of the improved repeater.

Using circuits shown in the repeater of Fig. 2 it will be realized that the number of impulses in a series transmitted over an outgoing trunk line is one less than the number in the incoming series. Although it is probably possible to arrange the numbering scheme so that this loss is unobjectionable, it is preferable that the impulses sent to the repeater should be transmitted from a register controller which may readily be arranged to send one or more impulses in each series

in addition to the number actually required for operating the automatic switches. As two repeater stages are shown in the office code translation, it is necessary that all digits stored in the register controller should be increased by two impulses as each repeater will absorb one of the additional impulses.

Referring now more particularly to Fig. 1, when the subscriber at substation A removes his receiver, line relay 102 energizes over line conductors 190 and 191 in series and earths private line conductor 196 at armature 109', thereby marking the calling line busy to the connector switches having access to it and closing a circuit for relay 101 and stepping magnet 104 in series. Line relay 102 at armature 100 also connects test wiper 198 to the junction of relay 101 and stepping magnet 104 and completes the following circuit for stepping magnet 104: earth, armature 109', home position bank contact 197, wiper 198, armature 105' and its resting contact, working contact of armature 100, interrupter contacts 199, stepping magnet 104 to battery. The circuits are such that the wipers will be rotated in a buzzer-like fashion until an idle trunk is reached. When an idle trunk is reached which trunk it will be assumed is the one comprising conductors 192-195, switching relay 101 being no longer short-circuited, energizes in series with stepping magnet 104. Stepping magnet 104, however, does not energize at this time on account of the high resistance of switching relay 101. Upon energizing, switching relay 101 prepares a circuit for the meter 103 at armature 106', opens the test circuit and prepares the holding circuit at armature 105', and at armatures 107' and 108' disconnects line conductors 190 and 191 from the windings of line relay 102 and earth respectively and extends them by way of wipers 180 and 181 to the conductors 192 and 195, leading to a disengaged first code selector FCS. The impulse responding relay 105 in the first code selector energizes over conductors 192 and 195 and at armature 159 completes the following circuit for guard relay 163: earth, armature 159, low resistance winding of relay 110, armature 135, winding of relay 163 to battery. Relay 163 operates in this circuit, but relay 110 does not. Relay 105 also completes at armature 111 a circuit for the impulse accepting relay 164 as follows: battery, upper winding of relay 164, resting contact and armature 156, normally closed contact controlled by armature 137, left-hand winding of polarized supervisory relay 106, working contact and armature 111, resting contact and armature 134, winding of high impedance relay 107, normally closed contacts controlled by armature 130, armature 153 and its resting contact, lower winding of relay 164 to earth. Relay 164 upon energizing completes at armature 152 the following

circuit for change-over relay 162: battery, relay 162, off-normal contacts N3 in normal position and working contact and armature 152, armatures 112 and 147 to earth. At the same armature relay 164 completes the following circuit for the delayed metering relay 108: battery, relay 108, working contact and armature 152, armatures 112 and 147 to earth. Relay 163 on operating performs the following functions: earths the release trunk 193 at armature 150, prepares a locking circuit for itself at armature 149, extends earth at armature 150 over start lead 175, home position private bank contact 518 of the A digit switch selector RS, shown in Fig. 5, private wiper 517, conductor 172, armature 132 and its resting contact, working contact and armature 142, armature 122 and its resting contact, conductor 171, driving magnet 516 of switch RS, to battery. Magnet 516 energizes and advances its wipers from their home position bank contacts in buzzer-like fashion until an idle A digit switch is reached. When an idle A digit switch is found the private wiper 517 of switch RS does not encounter earth and thus magnet 516 is not operated and a shunt which has been maintained across relay 160 during stepping of the wipers of the switch RS is removed. Relay 160 now operates in series with magnet 516 from earth over armature 149 and working contact, armatures 124 and 117, and their resting contacts, armature 143, relay 160, conductor 171, magnet 516, to battery, and is subsequently held energized in series with magnet 516 over its armature 132, conductor 172 and wiper 517, by earth potential fed back over the release trunk 560. Magnet 516 does not operate in series with relay 160 on account of the high resistance of relay 160. Relay 160 upon operating performs the following functions: completes at armature 135 a circuit for the impulse accepting relay 511 of the A digit switch from earth, armature 159, relay 110, armature 135 and its working contact, armature 126, conductor 170, wiper 526, armature 532 and resting contact, relay 511 to battery, at armature 130 maintains relay 164 energized over conductor 173 and at armature 137 connects up dial tone current to the incoming negative speaking conductor 192 as follows: negative speaking conductor 192, condenser C, condenser C2, armatures 138, 145 and 156, working contact and armature 137, conductor 174, wiper 520, resting contacts of armature 534, armature 539, springs S2, conductor DT, condenser C3 to earth and at armature 133 completes a locking circuit for relay 163. The operation of relay 511 in the A digit switch (Fig. 5) completes a circuit for guard relay 512 from earth, armature 531, armature 535, and its working contact, relay 512 to battery. Relay 512 operates and earths the release trunk conductor 560 at armature 538. This earth is 130

also extended over wiper 517, and serves to hold relay 160 as previously described. Relay 512 prepares the impulsing circuit at armature 536 and at armature 537 completes a circuit for time pulse relay 515. As soon as relay 160 operates the dial tone current is transmitted to the calling party in order to advise him that he may commence dialling the wanted number. The dial tone current is transmitted from the A digit switch ADS over one wiper of the outgoing impulsing circuit to the first code selector FCS where it is connected to an incoming speaking conductor by means of the small condenser C2. Relay 105 (Fig. 1) responds to the impulses transmitted by the calling party over the loop circuit comprising the incoming negative and positive speaking conductors 192 and 195, and repeats them at armature 159 over the single impulse conductor 170, the first series being transmitted to the impulse relay 511 of the A digit switch ADS and subsequent series to the various registers of the register controller taken into use by the A digit switch. It will be assumed that the register controller taken into use by the A digit switch is the register controller shown in Figs. 6 and 7. The path over which the first series is transmitted is earth, armature 159, low resistance winding of relay 110, armature 135 and its working contact, armature 126, conductor 170, wiper 526, relay 511 to battery. Relay 511 responds to the impulses repeated by relay 105 and transmits them to the vertical magnet 525 over the circuit: earth, armature 531, armature 535 and its resting contact, armature 536 and its working contact, relay 513, springs 53, vertical magnet 525 to battery. Relay 512 being slow to release, does not fall away during impulsing. Relay 513 energizes in series with magnet 525 and being slow-to-release remains energized during impulse transmission to the magnet. The vertical magnet 525 operates with each impulse and upon the first vertical step operates the off-normal springs N, N1 and N2. The springs N prepare a circuit for the release magnet 523, springs N2 open a point in the circuit of the time impulse relay 515, and springs N1 complete the following circuit for busy relay 514: battery, relay 514, springs N1, armature 540, armature 538 to earth. Relay 514 upon energizing completes a locking circuit for itself at armature 542, and at the same armature connects earth to one side of relay 510 over earth, armature 531, armature 542, and springs S4, the other side of relay 510 being earthed at armature 538 of relay 512. Relay 514 also prepares at armature 541 a circuit for the rotary magnet 524. At the end of the series of impulses to the vertical magnet 525, relay 513 releases and at armature 540 completes the following circuit for the rotary magnet 524: battery, magnet 524, armature 544, armature 541, armature 543 and resting contact, normal post springs NP which are operated on the first step only, contacts controlled by armature 540, armature 538 to earth. The rotary magnet 524 operates and breaks the interrupter springs 547 thus opening the circuit of relay 514 which now releases and opens the circuit of magnet 524 which also releases. The A digit switch wipers 520, 521, 522 and 528 are now in engagement with the first set of bank contacts and if these are busy the private wiper 521 picks up earth and the following circuit is completed for relay 514: earth, wiper 521, armature 533, springs S4, interrupter springs 547, springs N¹, relay 514 to battery. Relay 514 operates and completes the previously traced circuit for rotary magnet 524. The rotary magnet in operating breaks the circuit of relay 514 which restores and in turn breaks the circuit of the rotary magnet again. The above cycle of operations is repeated until an idle register controller such as shown in Figs. 6 and 7 is found, in which case the private wiper 521 does not find earth and relay 514 therefore is not re-operated. The absence of earth on private wiper 521 permits relay 510 to energize in series with relay 514 in the following circuit: battery, relay 514, springs N1, interrupter springs 547, springs S4, relay 510, armature 538 to earth. Relay 510 alone operates in this circuit, since relay 514 is so adjusted that it will not operate in series with relay 510. The operation of relay 510 switches the incoming pulse conductor 170 the private conductor 172 and the outgoing impulse conductors 173 and 174 through to the wipers 522, 521, 528 and 520 at armatures 523, 533, 570 and 534 respectively. Relay 510 at armature 531 opens a point in the circuit of release magnet 523 and at the back contact of armature 532 opens the circuit of relay 511. Relay 510 also disconnects the dial tone current from the calling line at armature 534. Relay 511 upon releasing opens the circuit of relay 512. Relay 512, however, does not fall away until after earth potential has been connected to the release trunk 560 over the private wiper 521 from the register controller. Relays 511 and 512 in de-energized position prepare a circuit for release magnet 523. The remaining series of impulses sent in by the calling party are repeated by relay 105 over pulse conductor 170 and wiper 522 to the various registers of the register controller shown in Figs. 6 and 7.

Referring now to Fig. 6, when the register controller is taken into use over conductors 661—664 the impulse accepting relay 629 is energized over earth from conductor 662. Relay 629 upon energizing, completes the following circuit for guard relay 632: earth, spring 642 and its resting contact of busy key BK, armature 611 and resting contact of cut-off relay 607, resting contact and ar-

mature 612 of release relay 608, armature 613 of relay 629 and its working contact, relay 632 to battery. Relay 632, upon energizing, prepares at armature 614 the impulsing circuit for office register OR and digit registers DR1—DR4; at armature 609 earths the release trunk conductor 661; at armature 615 completes a circuit for starting the motor (not shown) over conductor MS which drives 5 the loop pulse springs LPS, and magnet pulse springs MPS and the time pulse springs (not shown) to which the time pulse conductor T. P. E. fed through the time pulse disconnect key TPDK is connected; at armature 616 completes the following circuit for the two-step impulse control relay 624: earth, armature 616 and its working contact, armature 617 and its resting contact, resting contact and armature 618, loop 10 pulse springs LPS, armature 619 and its resting contact, upper winding of relay 624 to battery. Relay 624 partially energizes in this circuit and operates its armature 620 which connects up its lower winding. 15 When the loop pulse springs LPS open, relay 624 fully energizes over both its windings in series and at armatures 618 and 619 connects the loop pulse springs LPS to the outgoing positive and negative loop conductors 664 and 663 but as they are short-circuited by contacts 673 of relay 640 the impulses are not effective; at armature 621 relay 624 connects earth from conductor 627 to the home contacts in the bank of wiper 703 20 of the sender control switch SC and at armature 685 extends earth to the bank contacts other than the home contacts in the bank of wiper 601 of the switch SS. The earth on the home contacts in the bank of wiper 703 25 of the sender control switch SC is extended via wiper 703, conductor 674, magnet pulse springs MPS, armature 623 and its resting contact, armature 622 and its resting contact, upper winding of the two-step counting 30 control relay 625 to battery. Relay 625 only operates its armature 630 in this circuit which prepares a circuit for its lower winding. When the magnet pulse springs MPS open, relay 625 fully energizes over both its 35 windings in series, the circuit being: battery, upper winding of relay 625, resting contact and armature 622, lower winding of relay 625, working contact and armature 630, conductor 674 to earth over the previously traced 40 circuit for its upper winding. The operation of relay 625 extends earth at armature 690 to the driving magnet 706 of the sender control switch SC over the following circuit: battery, magnet 706, wiper 701 and normal 45 bank contact, conductor 691, armature 690, earth. Driving magnet 706 energizes and de-energizes in this circuit and advances its wipers on to the first set of contacts. This 50 operation breaks the circuit of relay 625 55 which accordingly de-energizes.

If for any reason the loop pulse springs LPS do not function correctly, the line impulse control relay 624 will not operate and if the magnet pulse springs MPS do not function correctly the impulse control relay 625 will not operate and in either case a circuit will be completed for the pulse alarm relay 606 at the end of the first series of impulses dialled by the calling party. The operations which take place when the calling party dials will now be described. The impulse accepting relay 629 responds to impulses dialled by the calling party. Relay 629 upon de-energizing transmits an impulse to the vertical magnet 705 of the office register OR over the following circuit: earth, spring 642 of busy key BK, armature 611 and its resting contact, resting contact and armature 612, armature 613 and its resting contact, working contact and armature 614, conductor 631, resting contact and armature 732 of 10th level relay 711, conductor 633, series relay 641, conductor 634, wiper 713 of digit distributor switch DD in normal position to vertical magnet 705 and battery. Relay 641 50 energizes in series with the vertical magnet 705 and being slow to release remains energized throughout the series of impulses. Relay 641 upon energizing completes the following circuit for slow release relay 610: battery, relay 610, working contact and armature 635, resting contact and armature 636 to the earth conductor 627. Relay 610, upon energizing, prepares a circuit at armature 637 for the rotary magnet 716 of the digit distributing switch DD, Fig. 7. At the end of the impulses transmitted to the vertical magnet 705 of the office register OR, slow series relay 641 will de-energize and during the interval that relay 641 is de-energized and relay 610 energized, the following circuit is completed for the rotary magnet 716 of the switch DD: battery, magnet 716, conductor 638, armature 637 and its working contact, resting contact and armature 635, resting contact and armature 636 to the earth conductor 627. Rotary magnet 716 accordingly 100 energizes and advances its wipers 713, 714 and 715 one step in which position wiper 713 connects up the rotary magnet 712 of the office register OR and wiper 714 extends earth to wiper 704 of the sender control switch SC over conductor 684, armatures 683 and its resting contact and conductor 682.

As the method of operation of the office register OR and the digit registers DR1—DR4 forms no part of the invention a further detailed description of this will not be given but a detailed description will, however, be given of the means whereby the standard circuits shown in Fig. 7 have been modified so that the register controller sends two extra impulses in each series to the repeater shown in Fig. 2, as this forms a part of the invention.

5 Relay 641 releases at the conclusion of the dialling of the B and C digits and extends earth at armature 635 to operate relay 707 in the following circuit: battery, relay 707, armature 718, distributing frame DF, conductor 651, resting contact and armature 635, resting contact and armature 636, springs 657 of busy key BK, armature 616 and its working contact, springs 642 of busy key BK to earth. 10 Relay 707 closes circuits to the driving magnets 720—728 of the register marking switches and also closes a circuit for slow-to-operate relay 708 as follows: earth, armature 717 and its working contact, winding of relay 708 to battery. Relay 708 operates and locks up to earth over conductors 642 and 627 and opens the circuit to the register marking switch magnets 720—723 at armature 740 so that the wipers of the register marking switches are advanced one contact. Relay 708 opens the circuit of relay 707 and this relay thereupon completes a circuit for relay 709 as follows: battery, relay 709, resting contact and armature 719, working contact and armature 730, 25 resting contact and armature 731 and then over the previously traced circuit to earth at the busy key BK. Relay 709 operates and closes a circuit for relay 710 at armature 732, and at its remaining armatures closes circuits for the register marking switch magnets 720—723. Relay 710 operates and opens the circuit of relay 709 so that the wipers of the register marking switch are advanced one 30 more step and at the same time locks itself to earth in the same manner as relay 708. It will now be seen that the register marking switches have been advanced two steps and it will be realized that all digits stored on the register marking switches will be increased by two impulses owing to the initial setting of the marking switch wipers. A maximum of twelve impulses can now be sent to the register marking switches so these switches will have to have at least twelve contacts. Rotary line switches could be conveniently used for these switches.

40 As soon as the B and C digits have been recorded in the register controller the latter sends out in known manner a code of impulses predetermined by the impulses received. These impulses are transmitted over a loop circuit including wipers 520 and 528 of the A digit switch, wipers 529 and 530 of the A digit switch selector RS, conductors 173 and 174, and windings of the impulse responding relay 164 in the first code selector FCS. Relay 164 restores with each impulse and repeats them to the vertical magnet 167 over the circuit: earth, armature 147, armature 112 and 45 resting contact, armature 152 and resting contact, armature 141; vertical magnet 167 to battery. The vertical magnet operates with each impulse and steps its associated wipers to the desired level. At the end of the first 50 series of impulses the following circuit for

the rotary magnet 166 is completed: battery, magnet 166, armature 139, resting contacts of armature 146, release trunk conductor 193 to earth. The rotary magnet 166 on operating steps its wipers onto the first set of bank contacts in the selected level and at its interrupter contacts 176 opens the locking circuit of stepping relay 161. Relay 161 releases and opens the circuit of the rotary magnet. Stepping relay 161 and rotary magnet 166 operate alternately until an idle trunk is found. Relay 165 is shunted during the hunting operation by earth picked up on the private wiper P on the one side and the release trunk earth on the other.

70 When an idle trunk such as the one extending through the repeater shown in Fig. 2 is found, private wiper P does not pick up earth and the shunt across relay 165 is broken. Relay 165 now energizes in series with stepping relay 161 as follows: battery, relay 161, springs N5, interrupter contacts 176, springs S1, armature 127 and its resting contact, relay 165, conductor 193 to earth. Relay 165 alone operates in this circuit, and completes 75 the following functions: prepares a locking circuit for itself at armature 155, switches the negative and positive speaking conductors 192 and 195 through to the next switch at armatures 156 and 153 and at armature 154 connects up the metering conductor 194. Relay 165 also opens the circuit of relay 164 which now releases.

80 The register controller now transmits impulses to operate the repeater R1 shown in Fig. 2 and it will be remembered that the register controller is arranged to transmit two more impulses in each series than is actually required for operating the automatic switches. When the repeater is seized over conductors 210 and 211 the impulse relay 202 will be operated in the circuit: earth, lower winding of relay 202, resting contacts of armature 212, conductor 211, calling loop, conductor 210, resting contacts of armature 213, upper winding of relay 202 to battery. Relay 202 operates over this circuit and at armature 214 closes a circuit for the guard relay 203. Relay 203 operates and at armature 216 earths the release trunk conductor 100 215 to guard the switch and hold up the preceding switches, at armature 217 completes the circuit for the polarizing winding of the electro-polarized relay 206, and at armature 218 prepares a circuit for relay 204. When 105 the next series of impulses is transmitted, relay 202 will de-energize in response to the intermittent opening of this circuit and upon its first de-energization will complete a circuit from earth, armature 214 and its resting contact, armature 218, winding of relay 204 to battery. Accordingly, relay 204 is operated, and due to its slow to release characteristic remains operated throughout the series of impulses. Hence when relay 202 re-energizes 110 115 120 125 130

a circuit is completed from earth, armature 214 and its working contact, armature 219, lower winding of relay 207 to battery, whereupon relay 207 operates and locks up to earth at armature 221 dependent upon relay 204. In consequence of the operation of relay 207 the loop to the switch ahead including impedance 205, upper winding of relay 206 and armature 223 is replaced at armatures 224 and 225 by a direct loop including armature 226. Hence in response to subsequent impulses relay 202 will produce interruptions in this loop and thus impulses will be transmitted to the distant switch. Relay 203 which is slow to release is of course maintained operated during impulsion. At the conclusion of the impulse series, relay 202 will be held energized so that relays 204 and 207 will de-energize after a slight interval and relay 206 and impedance 205 will again be connected up. The same sequence of operations takes place in response to each succeeding series of impulses and owing to the fact that the first impulse is always suppressed all the impulses repeated are of the same character. It is of course apparent that with the circuits shown the number of impulses in a series transmitted out over the outgoing trunk is one less than the number in the incoming series.

The impulse trains will next pass through the second repeater stage shown in Fig. 3, comprising an incoming selector S_1 , an intermediate selector S_2 and a repeater R_2 . The repeater R_2 will absorb one impulse in each series in the same manner as the repeater R_1 shown in Fig. 2 and will repeat the remaining impulses in each series over the line to the selector and connector switches S_3 , S_4 and S_5 shown in Fig. 4. When the switching relay in the connector S_5 energizes it completes a signalling circuit over wipers 410 and 411 and ringing current is transmitted over the called line to operate the bell at substation A'.

When the full connection has been set up and the called subscriber replies, current will be reversed back over leads 222 and 227 to cause the operation of relay 203. Relay 206 at armature 229 closes a circuit for relay 201 which at armatures 212 and 213 repeats back the reversal over conductors 210 and 211, and at armature 228 includes both windings of impedance 205 in the back bridge so as to improve transmission. Release is effected in the usual manner throughout the system when the calling party hangs up his receiver and it will not be necessary to give a description of this operation.

Thus according to the invention an improved impulse repeater has been evolved which is so arranged that all the outgoing impulses are repeated under the same conditions after the characteristics of the line have become steady, and there is thus much less danger of the apparatus at the distant end failing to respond to one or more of the

impulses because it is of a different character from the remainder.

What I claim as new and desire to secure by Letters Patent is:—

1. An impulse repeater for use in telephone or like systems in which the number of impulses in a series transmitted over the outgoing circuit by interrupting the same is less by a fixed number than the number received over the incoming circuit. 75

2. An impulse repeater for use in telephone or like systems in which circuit arrangements are provided for absorbing one of the initial impulses of a series so that conditions shall have become steady before impulses are transmitted over a loop comprising the outgoing circuit. 80

3. An impulse repeater for use in telephone or like systems in which the initial impulse of a series incoming to the repeater is absorbed and the remaining impulses only of the series are repeated by interrupting the outgoing circuit. 85

4. An impulse repeater for use in telephone or like systems in which a relay energized at the commencement of the first impulse of an incoming series prepares a circuit for a second relay which is energized on the termination of said impulse and thereupon connects up impulsion contacts for transmitting the remaining impulses of the series to the outgoing circuit. 90

5. In a telephone system, a local trunk, an inter-office trunk, a repeater individual to said trunks for connecting the same, means for transmitting a series of digit impulses over said local trunk, and means in said repeater for absorbing the first impulse of the series and for repeating subsequent impulses of the series over said inter-office trunk. 100

6. In a telephone system, a repeater, a local trunk terminating in said repeater, an inter-office trunk also terminating in said repeater, means for transmitting series of impulses over said local trunk, and means in said repeater responsive to said impulses for transmitting series of impulses over said inter-office trunk which differ by a fixed number from the impulses transmitted over the local trunk. 110

7. In a telephone system, a train of automatic switches, a register sender, means for registering the number of a called line in said register sender, and means in said register sender for transmitting series of impulses in accordance with the digits of the registered number to operate said switches, each of said series of impulses comprising more impulses than are required to operate the respective switches. 120

8. In a telephone system, automatic switches, a repeater, a register sender, means for registering the number of a called line in said register sender, means in the register sender for transmitting series of impulses 125

representing the digits of the registered number to said repeater, each of said series including an impulse for each unit of a registered digit and an additional impulse, and means in the repeater for absorbing an impulse of each series and for repeating the remaining impulses of the series to said automatic switches to operate the same.

9. In a telephone system, automatic switches, two impulse repeaters, a register sender, means for registering the number of a called line in said register sender, means in the register sender for transmitting series of impulses representing the digits of the registered number to the first repeater, each of said series including an impulse for each unit of a registered digit and two additional impulses, means in the first repeater for absorbing an impulse of each series and for repeating the remaining impulses of the series to the second repeater, and means in the second repeater for absorbing an impulse of each series and for repeating the remaining impulses of the series to said automatic switches to operate the same.

10. In a telephone system, an impulse absorbing repeater, a register sender for receiving and storing series of impulses representing the digits of a called line number, means in the register sender for transmitting series of impulses through or independent of said repeater to extend a connection to the called line, circuit arrangements effective in case the connection is to be extended independent of said repeater for causing the register sender to transmit series of impulses corresponding in number to the received series of impulses, and other circuit arrangements effective in case the connection is to be extended through said repeater for causing the register sender to transmit series of impulses each comprising one more impulse than the received series.

11. In a telephone system, impulse absorbing repeaters, a register sender for receiving and storing series of impulses representing the digits in the number of a called line, means in the register sender for transmitting series of impulses independent of or through one or more of said repeaters to extend a connection to the called line, circuit arrangements effective in case the connection is to be extended independent of said repeaters for causing the register sender to transmit series of impulses corresponding in number to the received series of impulses, and other circuit arrangements effective in case the connection is to be extended through one or more of said repeaters for causing the register sender to transmit series of impulses in which the number of impulses in each series is increased over the number of impulses in the received series by one impulse for each repeater through which the connection is to be extended.

12. In a register sender, means comprising

a two-motion register switch and a plurality of single-motion register switches for receiving and storing digit impulses, and means controlled by the receipt of a particular combination of digits by said first register switch for automatically operating said other register switches.

13. In a register sender for receiving and storing a plurality of series of impulses, a register switch set by the first two series of impulses received, a plurality of other register switches set, respectively, by subsequent series of impulses received, and means controlled by the setting of said first register switch for giving said other register switches an initial setting prior to the receipt of said subsequent series of impulses.

14. In a telephone system, a register sender for receiving and storing impulse series representing the digits of a called line number comprising an office-register switch set according to the first two digits of the called number, a plurality of digit-register switches set according to subsequent digits of the called number, and means controlled by said first register switch for operating said digit registers.

15. In combination with a register sender comprising a first register switch adapted to be set by remotely generated impulses and a plurality of other register switches adapted to be set jointly by remotely generated impulses and by locally generated impulses, of local impulse generating means, and means controlled by the setting of said first register switch for operating said local impulse generating means.

16. In a register, an impulse generator, a two-motion register switch adapted to be set by remotely generated impulses, a plurality of other register switches adapted to be set jointly by remotely generated impulses and by impulses from said generator, and means controlled by the setting of said first register switch for operating said generator.

17. In a multi-office telephone system, called lines identified by a number consisting of an office designation and a numerical designation, a register sender comprising an office register for receiving and storing the office designation of a called line and a plurality of digit registers for receiving and storing, respectively, the numerical designation of the called line, means responsive to the registration of a particular office designation on said office register for presetting said digit registers in one manner, and means responsive to the registration of a different office designation on said office register for presetting said digit registers in a different manner.

18. In a register sender comprising a first register switch on which are registered the first two digits of a called number, a plurality of other register switches on which are registered individually the subsequent digits of

the called number, an impulse sender controlled successively by said switches for transmitting series of impulses corresponding to the digits registered on said switches, and automatic means for operating said other registers prior to the registration of said subsequent digits, said means being operated responsive to the registration of a particular combination of digits on said first register switch.

In testimony whereof I affix my signature.
TREVOR H. TURNEY.
